SCREEN WIRE STRETCHING DEVICE

Filed Sept. 11, 1939

Fig. 1.

Fig. 2.

Fig. 3.

A technical line drawing of a mechanical assembly. The main body is a rectangular block with diagonal hatching. A vertical rod with a circular cross-section is attached to the top center. Two curved, wavy lines extend from the right side. Various numbers are used for labels: 1, 2, 3, 4, 5, 6, 7, 8, 9, 10, 11, and 12. Number 1 is at the bottom center, 2 is on the right side, 3 is at the top right, 4 is on the left side, 5 is on the left side of the central rod, 6 is on the left side of the main body, 7 is on the right side of the main body, 8 is at the bottom right, 9 is on the right side of the main body, 10 is at the top left, and 11 is on the left side of the central rod. Number 12 is on the left side of the main body, pointing towards the center.

SCREEN WIRE STRETCHING DEVICE

Frank B. Floyd, Wheatridge, Colo.

Application September 11, 1939, Serial No. 294,293

5 Claims. (Cl. 140—109)

This invention relates to a device for stretching screen wire on frames such as, for window screens, transoms and screen doors.

The application of woven wire screen to frames, such as door and window frames, by hand is both slow and tedious and for a first class job requires a high degree of skill. The result of this is that much time and material is wasted by persons who attempt to perform this task without the necessary training.

This invention, briefly described, comprises a clamp formed from two parallel blocks which are interconnected at their ends by means of eyebolts and which can be secured to the edge of a bench or a table. The lower block has threaded openings for the reception of wooden screws whose ends are rotatably connected with a transverse bar.

Having thus briefly described the invention, the same will now be described in detail, and for this purpose reference will be had to the accompanying drawing, in which:

Figure 1 is a perspective view showing the stretching device in operative position;

Figure 2 is a top plan view of the stretching device and the table on which it is supported;

Figure 3 is a side elevation of the part shown in Figure 2; and

Figure 4 is a fragmentary end elevation partly in section showing the manner in which the blocks are interconnected.

In the drawing reference numeral 8 designates a table or bench on which the work is supported and reference numerals 9 designate cleats on which the frame 10 rests. The frame, which has been designated by reference numeral 10, may be a window or a door frame and has been shown more or less diagrammatically.

The screen is tacked to the frame along the end member positioned to the left in Figure 1 and the screen or other material thus attached to the frame is extended through the space 12 between the clamps comprising blocks 2 and 3. It will be seen that both of these blocks are provided at their ends with inwardly extending slots for the reception of eyebolts 5 that are provided with butterfly nuts 6. The eyes of these bolts are pivotally connected to the block 2 by means of pins 11 in such a way that they can be swung outwardly in the manner shown in Figure 4 where a portion of the blocks have been shown in section to disclose the relationship between the eyebolts and the blocks and in which the inoperative position of the eyebolt has been shown by

full lines while the operative position has been shown by dotted lines.

The lower, or block 2, is provided near each end with a threaded opening for the reception of a wooden screw 1. These screws are of the type generally employed in connection with carpenter clamps and can be purchased ready made. In the present embodiment, the clamp comprising blocks 2 and 3 have been shown as attached to the edge of the table or bench by means of a plate 7 and screws which have been indicated by round dots. As far as this invention is concerned, it is immaterial whether the clamp is attached to the table or support, but in actual practice, where a large number of frames are to be provided with screen, it is usual to thus secure the clamps in place. The ends of the screws 1 engage a rectangular bar 4 against which one end of frame 10 abuts. The screen, which has not been shown, is fastened at one end to the frame as above described, and extends between the two blocks 2 and 3. The nuts 6 are turned down so as to clamp the screen firmly in place. After the screen has been secured to the frame and to the clamp, screws 1 are rotated so as to move the bar 4 towards the left when viewed as in the drawing, whereupon the point of attachment of the screen to the frame is moved towards the left, thereby tensioning the screen. By relative adjustment of the screws 1, the material can be stretched uniformly and will be entirely free from wrinkles which nearly always occur when a screen is applied manually. After the screen has been stretched to the amount desired, the edges are secured to the frame by means of tacks, after which the screws are loosened and the screen cut along the end of the frame nearest to the clamps. Another frame can now be put in place and a screen applied thereto in the manner above described.

The bar 4 is provided with openings for the reception of the ends of screws 1 in the manner shown in Figure 2 and therefore comprises a part of the stretching device which forms the subject of this invention.

It is obvious that the table 8 and the blocks 9 form no part of this invention. Plate 7 is useful whether or not it is employed for the purpose of attaching the stretching device to the table or bench as it does assist the worker in properly positioning the several parts.

From the above description it will be apparent that by means of the simple clamp shown on the drawing and described herein, the application of wire screens to door and window frames can be

greatly facilitated and that a workmanlike job can be performed by anyone, regardless of whether or not he is skilled in this particular art.

Having described the invention what is claimed 5 as new is:

1. A stretching device comprising a clamp formed from two parallel, substantially rigid jaw members arranged in superposed relation, means for securing the members in clamping relation, 10 said means comprising an element hingedly attached to the lower member and projecting above the top of the upper member, a pressure exerting member threadedly connected with the hinged securing element for engaging the upper clamping 15 member, the lower clamping member having a threaded opening adjacent each end, the axes of the openings being parallel with the clamping surfaces, and a screw operatively associated with each opening.
2. A stretching device, comprising in combination, two parallel, substantially rigid jaw members arranged in superposed relation, the ends of the members having registering slots, an eyebolt having its eye positioned in each slot in the lower 25 member, a pivot pin extending through the eye and through the member, said eyebolts being swingable into the cooperating slots in the upper member, clamping nuts on the bolts, the lower member having transverse threaded openings adjacent its ends, and screws in said openings, the jaw members serving to clamp a fabric, and the ends of the screws to engage a member to be moved.
3. A fabric stretching device for use in applying a fabric to a frame, comprising in combination, two parallel, substantially rigid clamping jaw members, arranged in superposed relation,

the ends of both members having registering slots, an eyebolt pivoted in each slot in the lower member and swingable into and out of the corresponding slot in the upper member, the lower member having a transverse threaded opening 5 adjacent each end, a screw operatively associated with each opening, one end of each screw having a handle portion and the other end a cylindrical projection, and a cross bar carried by the screws, the crossbar having openings for the reception of the cylindrical ends.

4. A stretching device in accordance with claim 3 in which the lower jaw member has secured to one side thereof a plate that extends below the lower surface thereof and which serves 15 to engage an edge of a support.

5. A screen stretching device for use in applying wire screen to a frame, in combination, a support, having a flat upper surface and an edge, a screen clamp comprising two superposed, substantially parallel jaw members, each having its ends provided with a notch, the notches in the two members registering, an eyebolt pivotally secured in each notch of the lower jaw member and swingable into and out of the corresponding 25 notch in the upper member, nuts on the bolts, the lower jaw having a transverse opening adjacent each end, a screw threadedly connected with each opening, one end of each screw having a handle portion for turning the same, the other ends having cylindrical axial projections, a bar connecting the ends of the screws, said bar having openings for the reception of the cylindrical projections, and a stop plate secured to one side of the lower jaw member and projecting below the 30 same for engaging the edge of the support.
